UNITED STATES PATENT OFFICE.

WALTER D. DAVIES, OF BROOKLYN, NEW YORK.

REPEATING-CLOCK.

SPECIFICATION forming part of Letters Patent No. 278,105, dated May 22, 1883.

Application filed March 23, 1883. (No model.)

To all whom it may concern:

Be it known that I, WALTER D. DAVIES, of the city of Brooklyn, in the county of Kings and State of New York, have invented a new and useful Improvement in the Repetition Strike-Movements of Clocks, of which the following is a specification, reference being had to the accompanying drawings.

In what are known as "repetition strike-movements" of clocks the locking-piece which locks the striking-wheel is acted upon to unlock the said wheel for allowing the repetition of the strike to be produced by means of a push-pin. This push-pin commonly protrudes through a special opening in the clock-case, and has provided for it a special guide in the case. According to my invention the said push-pin works through the post which supports the bell; and my invention consists, principally, in the combination, with the locking device which locks the striking-wheel, and with a hollow or partly hollow post which supports the bell, of a push-pin working through and sustained by said post, and adapted to move the locking device out of the way of the locking-wheel.

The invention further consists in certain details of construction hereinafter described and claimed, and illustrated by the accompanying drawings.

Figure 1 in the drawings is a front view of the striking part of a clock with my improvement applied, showing the case and the bell in section and the bell-post partly in section. Fig. 2 is a view at right angles to Fig. 1. Fig. 3 is a side view of the push-pin. Fig. 4 is a face view of certain parts of the striking apparatus.

A is the frame of the clock-case, to which the front plate, B, of the clock-movement is secured. This frame is represented as formed with a bracket or arm, A', to which is firmly secured the bell-supporting post C. This post may, however, be secured to the frame or to the clock-case in any convenient manner.

D is the bell, secured on a shoulder on the upper part of the post C by a nut, a, fitting a screw-thread on the post.

The striking mechanism employed in carrying out my invention may be of any suitable kind capable of producing a repetition. That which I have represented is the well-known

rack striking-movement, and only needs description sufficient to enable the manner of applying my invention to be understood.

55

J is the hammer.

E is the striking-wheel, furnished with the usual pin, b, for operating on the tail c of the hammer, and giving motion, in the usual way, to the locking-wheel F, and through it, in the usual manner, to the fly G. The locking-wheel F carries the locking-pin d, which stops against the locking-piece H, as shown in Fig. 4, at all times but when the clock is striking or when the locking-piece has been pushed out of the way of the said pin preparatory to striking, as shown in Fig. 1, at which time the said pin is temporarily locked by the lifting and warning piece I.

K is the rack, operated upon in the usual way by the gathering-pallet e, and held up in the usual way by the stop-pin f on the locking-piece, as shown in Fig. 4, while the locking-wheel F is locked.

L l is the push-pin for operating on the upper end of the lifting and warning piece I, to make the lower end of the latter push out the locking-piece H and unlock the locking-wheel, as shown in Fig. 1, in which view the push-pin is shown pushed in, the locking-pin d being temporarily caught by the spur g on the lifting and warning piece I, which will hold it till the pressure of the finger is removed from the push-pin. The push-pin L might in some clocks be a simple straight pin, the lower end 85 of which, protruding through the bottom of the bell-post, would impinge on and act directly upon the lifting and warning piece; but in the example represented the said pin, in order that the part l, which impinges on and

acts directly on the lifting and warning piece, may clear all the wheel-work of the clock-movement, has the said part l made in the form of an inverted L or elbow, which works through a longitudinal slot, i, in the front of the post. The spring n, for pushing and holding out the push-pin, is applied within the post, between a shoulder therein and the under side of the inverted elbow projection. This method of applying the push-pin through the bell-post makes a very cheap provision for making a repetition movement of any ordinary rack striking-movement which has the bell suitably arranged. The top of the bell-post is a convenient and

suitable place for operating the push-pin, and the simple provision of a hole through the bell-post as a guide for the pin obviates the need of a special guide and support for the pin.

5 The push-pin, instead of being made of a single piece of the form described, with the elbow part l integral with the straight part L , may be divided at l' into two pieces, separately fitted to the post, the upper piece, above the point l' , always impinging on the lower piece at that point, and being kept from being forced too far out of the post by being provided with the shoulder l'' below the cap-nut a of the hollow bell-post.

15 What I claim as my invention, and desire to secure by Letters Patent, is—

1. The combination, with the device for locking the striking-wheel of a clock, of a push-pin passing through or within the supporting-post of the bell, and adapted to act upon the

locking device for the purpose of unlocking the striking mechanism, substantially as herein described.

2. The combination, with the locking-wheel and the locking-piece, and with a hollow post 25 which supports the bell, of a pin passing through or within said hollow post, for actuating the locking-piece to produce the liberation of the locking-wheel, substantially as herein described.

3. The combination, with the locking-piece H, the lifting and warning piece I, the bell D, and its hollow post, of the pin L l, passing through the said post and impinging upon the said piece I, substantially as herein described. 35
